UNITED STATES PATENT OFFICE.

JOHN PRIMROSE, OF RICHMOND, NEW YORK, ASSIGNOR TO FOSTER WHEELER CORPORATION, OF NEW YORK, N. Y., A CORPORATION OF NEW YORK.

OIL HEATER.

Application filed March 7, 1925. Serial No. 13,709.

The general object of my invention is to provide an improved tubular heater, especially devised and adapted for use in heating oil in oil refining operations.

More specifically, the object of my invention is to provide simple and effective valve provisions for regulating the flow distribution through the different oil paths in a tubular oil heater having its tube elements connected to provide a multiplicity of flow paths each of which comprises a number of tube elements connected in series.

The various features of novelty which characterize my invention are pointed out with particularity in the claims annexed to and forming a part of this specification; but for a better understanding of the invention, its advantages and specific objects attained with its use, reference should be had to the accompanying drawings and descriptive matter in which I have illustrated and described preferred embodiments of my invention.

Of the drawings:

Fig. 1 is a vertical longitudinal section through the heater;

Fig. 2 is a transverse sectional view through the heater on the line 2—2 of Fig. 1;

Fig. 3 is a sectional detail of one of the regulating valves; and

Fig. 4 is an elevation showing the positions of the regulating valves.

In the apparatus shown in Figs. 1 and 2, A represents an oil heater, comprising a combustion chamber A' shown as adapted to be heated by the combustion of oil supplied at A². The rear wall of the combustion chamber is formed by a bridge wall A³, over which the products of combustion pass into the upper end of a heater chamber A⁴, from the bottom of which they pass out to the stack through the outlet A⁵. In the chamber A⁴ are arranged banks of horizontal tubular elements B, which may well be of the Foster type, i. e., steel tubes surrounded by cast iron tubular casing elements externally corrugated to increase the heat absorbing surface.

The tubular elements B are connected by return bends E or other connecting devices to provide a plurality of paths of flow through the tubes for the oil to be heated. As indicated by the broken lines X and Y in

Fig. 2, in the heater illustrated, there are two such paths of flow, each of which includes half of the tubes B in each of the horizontal rows. The oil enters the path of flow from the oil supply piping C through a chambered member D having two openings D' in its rear wall, one for each path of flow. In each of the openings D' is expanded or otherwise secured, one end of the initial tube element B of the series of connected tube elements forming the corresponding path of flow. After passing through the initial tube element B of the flow path, the oil passes successively through each of the other tubes in the corresponding half of the lower rows of tubes, then successively through each of the tubes in the corresponding half of the tube row above, and so on until it has passed through all of the tubes B forming the corresponding path of flow. The outlet end of the final tube element B of each path of flow is connected by a vertical tube F, and elbow fitting F' to a corresponding one of a series of tube elements G incorporated in the roof of the furnace.

In practice the elements G are advantageously connected in series to form extensions of the two paths of flow into which the tube elements B are divided, the two flow path extensions discharging into a common outlet H. Advantageously, also, as shown, portions of the tubes G immediately above the chamber A⁴ are encased in metallic blocks G', and the remaining portions of the tubes G are encased in fire brick blocks G², but as these features of construction are not novel elements of the present invention, they need not be further illustrated or described herein.

The chambered member D, as shown, comprises an upper box-like portion in the flat rear wall of which the two openings D' are formed. As shown, the part D also comprises a horizontal flanged portion D³ by which the chamber D is connected to the oil supply pipe C. The distribution of flow between the two flow paths is controlled, in accordance with the present invention, by means of adjustable throttling devices or valves L located in the chamber D and separably movable in the latter chamber toward and away from the position in which each extends into and sub-

stantially closes the inlet end of the corresponding tube B. The simple and effective construction illustrated for supporting and adjusting the throttling devices L, comprise 5 a threaded valve spindle J for each member L which is co-axial with the corresponding tube B. Each spindle J passes through a threaded opening in a plug part I screwed into an opening D² in the front wall of the 10 member D which is co-axial with the corresponding opening D'. The outer end of each spindle J is provided with a handle J' by which the spindle J may be rotated to advance and retract the corresponding device L, and 15 each plug I is provided at its outer end with a stuffing box K for preventing leakage along the spindle. The plugs I take the place of hand hole covers for the openings D², the latter being necessary in any event to permit access to the tubes B secured in the openings D'.

In the operation of a heater of the type illustrated and described in which there are a plurality of elongated flow paths, it has heretofore been found difficult to attain the proper 25 distribution of flow among the different flow paths. With unequal rates of flow in the different flow paths, the oil will be heated to a higher temperature in a path in which the flow is relatively slow, than in a path in which 30 the rate of flow is relatively high. Owing to carbon deposits and other causes, it is difficult to maintain uniform frictional resistance to flow in the two paths. Any decrease in the rate of oil flow through one path as compared 35 with that through another and the increased oil temperature in the one path increases the vapor liberation in that path, and the increased rate of vapor liberation of itself, tends to increase the frictional resistance to flow in 40 the path and thus to further reduce the amount and increase the temperature of the oil passing along that path. Substantially equal rates of flow in the two paths are thus highly desirable. The regulating devices L 45 provided in accordance with the present invention, form simple and effective means by which on an increase in flow through one path above the rate of flow through the other path, the one path can be throttled, or the other path 50 opened up to restore the desired equal distribution of flow among the two paths. The actual distribution of flow among the different paths can be readily determined by measuring the oil temperature at the outlet ends of the 55 different paths, or at suitable intermediate points. The thermometers T, or other oil temperature measuring devices, the indications of which are to govern the adjustments of the devices L, can be conveniently located in the 60 elbow fittings F', which for this purpose are each provided with a thermometer well F² for the corresponding thermometer T. When one thermometer T indicates a higher temperature than does the other thermometer, one or 65 both of the devices L are adjusted to increase

the rate of flow in the flow path in which the higher temperature is indicated, as compared with the rate of flow through the other path. Preferably, and as shown, each device L is in the form of a cylindrical body with a conical inner end portion, and is of a maximum diameter slightly less than the bore of the tube B which it enters. This permits of an adjustment of each device L to make the flow through the corresponding flow path quite 75 small, but does not permit the flow through either path to be entirely stopped which is desirable, as the entire flow stoppage in either path would give rise to a dangerous and injurious condition. With the heater A once in 80 regular operation with the flow equally divided between the two flow paths, the devices L ordinarily require but little attention or adjustment, but when such adjustment is required it can readily be made.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims, and that in some cases certain features of my invention may be used to advantage without a corresponding use of other features.

Having now described my invention, what I claim as new and desire to secure by Letters Patent, is:

1. In an oil heater, the combination with a multiplicity of tubular elements and end connections providing a plurality of similar flow paths for the oil to be heated, each comprising a number of said elements connected in series, of a chambered supply member into which the inlet end of the initial element of each of said series is connected, and flow distribution controlling means comprising a separate flow regulating device for each flow path mounted in said chamber and adjustable to 100 variably obstruct flow into the inlet end of the corresponding initial element.

2. In an oil heater, the combination with a multiplicity of tubular elements and end connections providing a plurality of similar flow paths for the oil to be heated, each comprising a number of said elements connected in series, of a chamber supply member into which the inlet end of the initial element of each of said series is connected, and flow distribution controlling means comprising a separate flow regulating device for each flow path mounted in said chamber and adjustable to 110 variably obstruct flow into the inlet end of the corresponding initial element, each said device comprising a part of smaller diameter than the bore of said element and co-axial with and adjustably axially of the latter.

3. In an oil heater, the combination with a 130

multiplicity of tubular elements and end connections providing a plurality of similar flow paths for the oil to be heated, each comprising a number of said elements connected in series, of flow distribution controlling means comprising a separate flow regulating device for each flow path which is adjustable between maximum and minimum flow positions and is incapable of entirely closing off flow through the path to which it pertains when ¹⁰ in its said minimum flow position.

Signed at New York city, in the county of New York and State of New York, this 4th day of March, A. D. 1925.

JOHN PRIMROSE.
